UNITED STATES PATENT OFFICE

112,744

DESIGN FOR A BASE FOR PICTURE FRAMES OR THE LIKE

Evelyn Kratman, Chicago, Ill.

Application December 9, 1936, Serial No. 66,410

Term of patent 3½ years

To all whom it may concern:

Be it known that I, Evelyn Kratman, a citizen of the United States, residing at Chicago, in the county of Cook and State of Illinois, have invented a new, original, and ornamental Design for a Base for Picture Frames or the Like, of which the following is a specification, reference being had to the accompanying drawing, forming part thereof, in which:

Figure 1 is a perspective view looking down on the base from approximately straight in front of the stand.

Figure 2 is a front elevational view of the base; and

Figure 3 is a plan view of the base for picture frames or the like.

My design is characterized by a pair of plates having located between them spaced glass balls or agates which project above the top plate and below the bottom plate, the balls or agates being visible between the plates.

The agates are of a color contrasting with the color of the plates and are reflected therein. The dotted line showing of the picture frame is merely illustrative.

I claim:

The ornamental design for a base for picture frames or the like, substantially as shown and described.

EVELYN KRATMAN.
